UNITED STATES PATENT OFFICE.

NORMAN DODGE, OF EAST ORANGE, NEW JERSEY, ASSIGNOR TO MERGENTHALER LINOTYPE COMPANY, A CORPORATION OF NEW YORK.

PI-STACKING DEVICE FOR TYPOGRAPHICAL MACHINES.

1,078,612.

Specification of Letters Patent.

Patented Nov. 18, 1913.

Application filed October 7, 1911. Serial No. 653,443.

To all whom it may concern:

Be it known that I, NORMAN DODGE, a citizen of the United States, and a resident of East Orange, county of Essex, and State 5 of New Jersey, have invented a new and useful Improvement in Pi-Stacking Devices for Typographical Machines, of which the following is a specification.

My invention relates to typographical machines, and more particularly to that class thereof known to the public under the name "linotype" and as illustrated for instance in Letters Patent of the United States to O. Mergenthaler, No. 436,532. In machines of 15 this type it is the common practice to make use of matrices representing characters other than those controlled by the key-board. These extra or sorts matrices are inserted by hand into the matrix-line in the course of 20 composition, and are subsequently delivered by the distributor at a common point, from which ordinarily they descend by gravity through a receiving tube into a pi-stick or receptacle at the front of the machine. Such 25 a mechanism, generally speaking, is old in the art and is shown in Letters Patent of the United States to J. R. Rogers, No. 630,112. In the more advanced and refined 30 practice, machines have been devised where-in are employed a plurality of movable or adjustable magazines, any one of which may be brought into operative position with reference to the key-board and distributing mechanism at will. Such a plurality of 35 magazines is intended to provide a larger and more varied assortment of characters, which in turn may be again supplemented by the employment of additional or sorts matrices that are more rarely used and are 40 not contained within the magazines or represented by the key-board. These sorts correspond more or less in face or style to the particular face or style carried by the magazine in operative position, and it is therefore 45 desirable that they should be segregated in the same way that the primary matrices in the magazine are kept separate. To this end, therefore, I provide a plurality 50 of pi-stacking devices in combination with automatic means whereby the appropriate one will be brought into operative position, so that the sorts appertaining to each magazine will be received in a separate stick or receptacle, and will be readily available to 55 the compositor without the necessity of

searching through a mixed mass thereof to discover the particular face or style desired.

My invention may be specifically applied in a variety of different forms, and in the accompanying drawings I have illustrated 60 three distinct embodiments thereof. Generally speaking, I desire it to be understood that I do not limit myself to any specific form or embodiment except in so far as such limitations may be specified in the claims. 65

The particular machine in connection with which I have shown my invention is that set forth in the application of John R. Rogers for Letters Patent, No. 624,426, filed May 1, 1911, wherein is disclosed a plurality of movable magazines together with appropriate mechanism for selecting and shifting them and for locking them in adjusted position.

Referring to the drawings: Figure 1 is a 75 side view of the lower ends of the shiftable magazines with my invention applied thereto, partly broken away to show the operative parts more clearly; Fig. 2 is a front view thereof; Fig. 3 is a side view illustrating another form of my invention; and Fig. 4 is a side view of a third embodiment.

The magazines A¹, A², A³ are mounted in the frame A, and are or may be shifted and held in operative relation to the other parts 85 in the manner described in the said Rogers application, these particular adjusting and locking devices constituting no part of my present invention. As will be understood by those skilled in the art, the matrices representing characters other than those controlled by the key-board are inserted by hand into the matrix-line in the course of composition, and are automatically delivered by the distributor at a common point, as 90 set forth, for example, in the Letters Patent to P. T. Dodge, No. 539,985. The particular form of the distributing devices also constitutes no part of the present invention and needs no specific description herein. 100 Fig. 1, however, shows in dotted lines the ends of the distributing screws B, whereby the sorts matrices are delivered into the tube C, through which they pass into a sorts stick or receptacle in convenient proximity to the compositor. In the present instance three such sticks or receptacles A¹¹, A¹², and A¹³ are illustrated, each of them provided with the customary feeding or star-wheel F, which is rotated by a belt G, in substan- 110

tially the same manner as set forth in the Rogers patent, No. 630,112.

In the form illustrated in Figs. 1 and 2, the pi-sticks or receptacles A^{11} , A^{12} and A^{13} , 5 are stationary, and a single delivering means is employed in connection therewith, in the form of the movable flexible tube C, which is caused to register and connect with one or the other of the sticks or receptacles according to the position of the magazines. The lower end of the tube C is mounted in a 10 swinging arm D pivoted at E to the stationary machine frame, the position of the arm being controlled by the link H^1 connected thereto and to the elbow-lever H, which in turn is connected to the magazine-frame A. As shown in the drawing, the magazine A^2 is in operative position and the tube C registers with the corresponding stick 15 or receptacle A^{12} . When the frame A is raised, as shown in dotted lines, to bring the magazine A^3 into operative position, through the connections previously described, the tube C is swung to the left so as 20 to register with the corresponding stick or receptacle A^{13} . Similarly, when the frame A is lowered, as shown in dotted lines, to bring the magazine A^1 into operative position, the tube C is swung to the right so as 25 to register with the corresponding stick or receptacle A^{11} . Each of the sticks or receptacles is formed with a notch J adapted to engage the spring-pressed detent D¹ on the arm D and thus to hold the tube C in proper 30 adjusted relation.

Fig. 3 illustrates a somewhat similar arrangement, wherein, however, the member D is formed with a projecting arm L carrying a roll L¹, which is held by a spring M in engagement with a cam piece K connected to the frame A. As the frame A is moved, and through the connections described, the member D, and hence the bottom of the flexible tube C, is brought into registration with the 40 corresponding stick or receptacle substantially in the manner previously described. The cam piece K is formed with cuts or notches K¹ to hold the member D in proper adjusted relation to the other parts.

50 In Fig. 4 I have illustrated still another type, wherein the tube is stationary and the sticks or receptacles are adjusted in relation thereto. In this instance, the three sticks A^{111} , A^{112} , A^{113} are slidably mounted and 55 are connected by link N², elbow-lever N², link N¹ and lever N, to the magazine-frame, in such manner that the shifting of the magazines and their frame effects the simultaneous adjustment of the sticks or receptacles 60 so as to bring the corresponding one into proper relation to the tube C. It is to be noted that in this instance, the receptacles are reversed in position as compared with the form illustrated in Figs. 1 and 2, the dif-

ference arising from the fact that the sticks 65 are moved instead of the tube. This arrangement also renders desirable a slightly different means for rotating the feeding or star-wheels, the lower one being actuated by the band G¹, and the two upper ones by the 70 band G² driven from the lower one.

It will be seen that in all three forms I have illustrated a plurality of pi-stacking devices, which are automatically controlled, so that each will be brought into operative 75 position in relation to its corresponding magazine. Obviously many other variations and modifications will suggest themselves to those skilled in the art without departing from the spirit or scope of my invention. 80

Having thus described my invention, its construction and mode of operation, what I claim and desire to secure by Letters Patent of the United States is as follows:

1. In a typographical machine, the combination of a plurality of movable magazines, a corresponding plurality of adjustable pi-stacking devices, and connections whereby the movement of the magazines effects the adjustment of the pi-stacking devices. 85

2. In a typographical machine, the combination of a plurality of movable magazines, a corresponding plurality of movable pi-sticks or receptacles, and connections whereby the movement of the magazines effects 95 the movement of the said sticks or receptacles.

3. In a typographical machine, the combination of a plurality of movable magazines, a plurality of adjustable pi-stacking devices, 100 and connections whereby the movement of any selected magazine to operative position effects the similar adjustment of the corresponding pi-stacking devices.

4. In a typographical machine, the combination of a plurality of magazines, a corresponding plurality of adjustable pi-stacking devices, and means whereby a selected magazine may be brought into operative relation 105 to the other parts and a corresponding pi-stacking device simultaneously adjusted.

5. In a typographical machine, the combination of a plurality of magazines, and a corresponding plurality of adjustable pi-stacking devices, comprising a plurality of 115 pi-sticks or receptacles and a common means for delivering the type or matrices thereto, with means whereby a selected magazine may be brought into operative relation to the other parts and simultaneously the corresponding stick or receptacle connected to the 120 common delivering means.

6. In a typographical machine, the combination of a plurality of magazines, a corresponding plurality of adjustable pi-sticks or 125 receptacles, a common means for delivering type or matrices thereto, and means whereby the sticks or receptacles are shifted to bring

any one of them into relation to the common delivery means when the corresponding magazine is brought into operative relation to the other parts.

7. In a typographical machine, the combination of a plurality of movable magazines, a corresponding plurality of pi-receptacles, and means whereby, when a selected magazine is moved into operative position, the

corresponding pi-receptacle is connected to therewith.

In testimony whereof I hereunto set my hand this fifth day of October, 1911, in the presence of two attesting witnesses.

NORMAN DODGE.
